E. Elmir J. May, of Lowell, Mass.
Assignor to
Lowell Manufacturing Company, of same place.
Letters Patent No. 1084, dated, July 15, 1859.

Wes 1084

2

The Schedule referred to in these Letters Patent and making part of the same. —

To all whom it may concern:

Be it known that I, Elmer J. May, of Lowell in the County of Middlesex and State of Massachusetts have originated and designed a new pattern for Carpet, or other fabrics of which the following, taken in connection with the accompanying drawing, is a full, clear and exact description —

The corners 1 and 2, consist each of a quarter circle comprised of lace work f and sprigs g, which being matched with three broadths of Carpet, form the entire medallions. No 1, being surrounded by the circle of sprigs g, and No 2, by the border R. —

The corners 3 and 4, are composed each of a quarter of a garland — which when the broadths of Carpet are matched, form a whole garland with lace work in the center. —

Between the four corners and in the center of the figure are the apples h. —

The colors employed for the different portions of the design may be varied to suit the taste and wishes of the manufacturer. —

Claim —

What I claim as my invention and desire to secure by letters patent is the within described design or Pattern for Carpet and other fabrics. —
